CLOTHES BRUSH

Russell S. Cline, Statesville, N.C.; Charles C. Cline, administrator of said Russell S. Cline, deceased

Filed Aug. 20, 1969, Ser. No. 18,767

Term of patent 14 years

Int. Cl. D28—03; D4—02

U.S. Cl. D86—13

FIG. 1

FIG. 2

FIG. 4

FIG. 1 is a top perspective view showing my new design;

FIG. 2 is an end view;

FIG. 3 is a top plan view; and

FIG. 4 is a bottom plan view.

The net fabric is understood to continue uniformly throughout the area of the brush.

I claim:

The ornamental design for a clothes brush, as shown and described.
